MANIFOLD HEATER

John S. Huber, South Milwaukee, Wis., assignor
to Nash-Kelvinator Corporation, Kenosha, Wis.,
a corporation of Maryland

Application July 3, 1940, Serial No. 343,773

8 Claims. (Cl. 123—122)

This invention relates to manifold heaters and has particular reference to means for controlling the temperature of the fuel mixture in an intake manifold cast in an internal combustion engine.

It is an object of this invention to provide a manifold which will be properly heated at all times.

It is another object of this invention to provide a heater passage in the block of an internal combustion engine for maintaining a suitable temperature in the intake manifold.

It is another object of this invention to provide means for heating an intake manifold, which means will maintain a constantly suitable temperature in the manifold without controls or moving parts.

It is another object of this invention to provide an intake manifold which is subject to the combined action of exhaust gases and cooling water in such a manner as to maintain a constantly suitable temperature.

Other objects and advantages of this invention will be apparent from a consideration of the following description and claims and the attached drawing of which there is one sheet and in which—

Figure 1 represents a front elevation of the upper portion of an internal combustion engine of the L-head type;

Figure 2 represents a vertical sectional view taken along a plane indicated by the line 2—2 in Figure 1 and looking in the direction of the arrows;

Figure 3 represents a transverse sectional view taken along a plane indicated by the broken line 3—3 in Figure 2 and looking in the direction of the arrows;

Figure 4 represents a transverse sectional view taken along a plane indicated by the line 4—4 in Figure 2 and looking in the direction of the arrows.

It is a well established fact that better carburetion and combustion in an internal combustion engine is obtained by maintaining the fuel mixture at the proper temperature which is usually higher than the temperature of the air surrounding the intake manifold and carburetor. It is also well established that too high a temperature will cause the fuel mixture to explode too soon in the engine and is generally detrimental to the operation of the engine. The need for heat in the intake manifold is particularly noticeable when the engine is first started after being allowed to be cooled for some time. In the past it has been the practice to conduct exhaust gases to some

sort of a heater or stove around a portion of the intake manifold. Various types of manual and automatic shut-off devices were employed to cut down the flow of gases to the heater as the engine became warm and the demand for heat was reduced. In this invention heat is applied to the intake manifold by providing a chamber directly underneath the intake manifold, which chamber is in open communication with the exhaust system of the engine. The temperature in the intake manifold is maintained within the desired operating limits by constructing the chamber under the intake manifold in such a manner that the greater portion of the exhaust gases will not enter the chamber when the engine is operating at high speed. The temperature of the intake manifold is further controlled by subjecting the intake manifold and the heater chamber to the action of the cooling water in the engine, thus at low speeds, as are encountered in starting an engine, a greater portion of the exhaust gases remain in the heater chamber for a greater length of time and there is less circulation of cooling water around the chamber, while at high speed a greater proportion of the exhaust gases pass directly out of the engine without affecting the intake manifold and both the heater chamber and intake manifold are subjected to a more vigorous circulation of the cooling water. The above heat regulating system is accomplished without controls or movable dampers by an arrangement of the intake manifold and exhaust passages with respect to the cooling jacket of the engine, an example of which will now be more particularly described.

Illustrated in the drawing is an internal combustion engine generally indicated at 10 having a block 12 and a head 14. The head 14 is secured to the block 12 by the usual head bolts 16 and carries the usual spark plugs 18 and a down draft carburetor 20. The block 12 carries along the side thereof a tubular exhaust manifold 22 secured to the block by a series of clips 24 and bolts 26. The usual head gasket 28 is provided between the head 14 and block 12.

Formed along one side of the block 12 is an overhanging portion 30 within which is cast a longitudinally extending intake manifold 32 which is open along the top surface of the block. Carburetor 20 discharges into the manifold 32 through port 33 formed in the head 14. From the intake manifold 32, ports 34 open into intake passages 36 (see Figure 4) which may be siamesed to accommodate two cylinders and which are controlled by intake valves 38 to admit the fuel

mixture to combustion chambers 40 formed on the under surface of the head 14.

Between the intake passages 36, exhaust passages 42, controlled by exhaust valves 44, extend downwardly from the combustion chambers 40 and pass out through the overhanging portion 30 immediately underneath the intake manifold 32. The exhaust pipe 22 is provided with apertures 46 which connect with the passages 42 to allow the exhaust gases to enter the exhaust pipe. It is to be understood that the exhaust passages 42 each connect to one or two combustion chambers 40, and that several of the passages are provided as shown in Figure 2.

Between the several passages 42 and directly underneath the intake manifold 32 is formed a longitudinally extending chamber 48 which connects the several exhaust passages 42. It is to be noted that the bottom wall of the intake manifold 32 forms the top of this heater chamber 48 so that there is direct heat transfer between the manifold and chamber.

The space between the intake passages 36 and exhaust passages 42 is surrounded by cooling water space 50 which is in communication with the water jacket 52 around the cylinder wall 54. Particular attention is called to the fact that the cooling water space 50 extends completely along the under side and ends of the heater chamber 48 and along the inside thereof between the exhaust passages 42.

The head casting 14 which forms the combustion chambers 40 and closes the intake manifold 32 is also provided with the familiar cooling water space 56 which is connected with the cooling water space 50 and 52 in the block 12. The valves 38 and 44 are positioned in guides 58 and extend downwardly through bosses 60 to a valve spring chamber 62 in a manner which is well known in automotive construction. The usual valve springs 64 and adjusting mechanism 66 is provided.

Particular attention is called to the fact that the exhaust passages 42 discharge directly into the opening 46 in the exhaust pipe 22 and directly across the heater passage 48. When the engine is running at slow speed as when it is being started, the interval between the exhaust charges passing through the various passages 42 is relatively large and there is time for the exhaust gases to surge back and forth along the heater passage 48 and give up some of their heat to the common wall between the heater passage and the intake manifold. At high speeds not only will the charges of exhaust gas come more rapidly due to the higher speed of the pistons expelling them, but they will come closer together so that there will be very little differential in pressure between one end of the heater passage 48 and the other. As a result most of the gases will pass directly across the heater chamber 48 into the exhaust pipe 22 without having much heating effect on the intake manifold. While the entire cross sectional area of the heater chamber 48 is shown to be open to the exhaust passages 42, it might be desirable in some engines to restrict the opening between the heater chamber and exhaust passages.

At high speeds, the differential in temperature between the walls of the heater chamber 48 and the water in the cooling passages 50 becomes higher so that a greater amount of the heat in the heater chamber 48 flows into the cooling water than to the intake manifold 32. There is also a more rapid circulation of the water

at high speeds. The combined effects of the gases passing directly through to the exhaust pipe and the increased effect of the cooling water on the heater chamber prevents the temperature in the intake manifold from rising too high. It is thus apparent that the intake manifold is provided with a large heater surface to quickly and effectively heat the fuel mixture when the engine is starting, which passage is so arranged as to reach a maximum efficiency above which it will not impart heat to the intake manifold. The various passages are easily and cheaply cast along with the rest of the block and require no extra machining over a block without the heater chamber. The heat control is entirely automatic and has no moving part or thermostat to become out of order. While the example illustrated is an engine of the L-head type, the same principle is readily adaptable to a valve-in-head engine and can be applied to engines having intake manifolds mounted separately from the block or head castings.

While I have described my invention in some detail, I intend this description to be an example only and not limiting on my invention to which I make the following claims:

1. In combination with an internal combustion engine having an intake manifold, a heater chamber adjacent to said manifold, an exhaust passage opening from said engine into said heater chamber and continued therebeyond across a short dimension of said heater chamber, an exhaust pipe connected to said passages on the opposite side of said heater chamber from said engine, and a cooling water jacket formed around said intake manifold and heater chamber.

2. In combination with an internal combustion engine having an exhaust pipe an intake manifold in a wall of said engine, a heater chamber adjacent said intake manifold, exhaust passages in said engine extending from said engine to said exhaust pipe, said heater chamber communicating with the exhaust passages intermediate the ends thereof through the sides of the passages, and a water jacket formed around said intake manifold, heater chamber and a portion of each of said exhaust passages.

3. In combination with an internal combustion engine having an intake manifold, an elongated heater chamber adjacent to said manifold, exhaust passages opening into said heater chamber and directed across a short dimension of said heater chamber, a wall of said heater chamber defining ports opening into an exhaust pipe, said ports being directly opposite said exhaust passages, and a cooling water jacket formed around said intake manifold and heater chamber.

4. In combination with an internal combustion engine having an elongated intake manifold cast therein, exhaust passages cast in said engine and extending from the cylinders thereof across a wall of said manifold, a heater chamber positioned adjacent to said manifold and communicating with said exhaust passages, said exhaust passages extending beyond said heater chamber through a side wall of said engine, and a water jacket cast around said intake manifold, exhaust passages and heater chamber.

5. In combination with an internal combustion engine having an intake manifold cast therein, an exhaust pipe, a heater chamber cast along one wall of said manifold, a plurality of exhaust passages cast in said engine, said exhaust passages intersecting said heater chamber at right

angles and extending therebeyond to said exhaust pipe, and a cooling water jacket cast around said intake manifold, heater chamber and exhaust passages.

6. In combination with an internal combustion engine having an intake manifold cast therein, a heater chamber cast along one wall of said manifold, a plurality of exhaust passages cast in said engine and intersecting said heater chamber at right angles, said exhaust passages extending on each side of said heater chamber to the side of said engine and to the cylinders thereof, and a cooling water jacket cast around said manifold, heater chamber and exhaust passages.

7. In combination with an internal combustion engine having an intake manifold, an exhaust system for said engine having parallel passages connected at several points, one of said parallel passages being adjacent said intake

manifold, said last mentioned passage being positioned between the cylinders of said engine and the other of said passages, and a cooling water jacket formed around said intake manifold and the passage of said exhaust system adjacent said manifold.

8. In combination with an internal combustion engine having an intake manifold, a plurality of exhaust passages extending at right angles to said manifold, an exhaust manifold located at the ends of said exhaust passages, a heater chamber parallel with said exhaust manifold and intersecting said exhaust passages, said heater chamber being adjacent said intake manifold and between said exhaust manifold and the cylinders of said engine, and a cooling water jacket formed around said intake manifold, exhaust passages and heater chamber.

JOHN S. HUBER.
